P. B. CAMP

WINDING MECHANISM

Filed Oct. 5, 1925

UNITED STATES PATENT OFFICE.

PERCY B. CAMP, OF MAYWOOD, ILLINOIS, ASSIGNOR TO UNIVERSAL DRAFT GEAR ATTACHMENT CO., A CORPORATION OF ILLINOIS.

WINDING MECHANISM.

Application filed October 5, 1925. Serial No. 60,407.

This invention relates to winding mechanisms particularly adapted for hand brakes on railway cars, and has for its chief object to permit the principal parts of the mechanism to be supplied as an assembled unit that may be readily installed on the car, and to eliminate binding against the bearings that might otherwise result from imperfect installations.

10 Other objects and advantages of the invention will become apparent as the disclosure proceeds and the description is read in connection with the accompanying drawings, illustrating the preferred embodiment 15 of the invention, and in which—

Fig. 1 is a plan view of a fragment of a railway car with a winding mechanism embodying the invention applied thereto;

Fig. 2 is a sectional view taken on the line 2—2 of Fig. 1;

Fig. 3 is a sectional view taken on the line 3—3 of Fig. 2;

Fig. 4 is a sectional view taken on the line 4—4 of Fig. 3;

25 Figs. 5 and 6 are perspective views of component parts of the sleeve used in this preferred embodiment to swivel the various parts together, and

Fig. 7 is a fragmentary sectional view illustrating a slight modification by which the structure is adapted to use with a square shaft.

A conventional brake staff is shown at 10 journalled at its lower end in a bar or step 35 11 and at its upper end in a bearing 12 carried by a bracket 13, secured to a railway car indicated by the fragment 14.

The shaft is wound by a ratchet and pawl mechanism including a ratchet wheel 15, 40 mounted to rotate with the shaft 10, a hand lever 16 mounted to rotate about the shaft and equipped with a pawl 17 cooperating with the ratchet wheel, whereby swinging the hand lever between the dotted line 45 positions A and B in Fig. 1 will result in rotating the shaft clockwise in that figure.

The shaft is held against unwinding by a pawl 18 mounted at 19 in the bracket 13 and having a counter-weighted heel 20 constantly urging the pointed toe 21 into engagement with the ratchet wheel.

In this preferred embodiment the bracket 13, the ratchet wheel 15 and the hand lever 16 are assembled upon a sleeve 22 which 55 serves to hold these parts together as a

unit. In the particular form shown the sleeve is made of four longitudinal sections, three having the form indicated at 23 (Fig. 6) and one having the form indicated at 24 (Fig. 5). The upper ends of the sections 60 are provided with flanges 25 and 26 which have projections 27 adapted to seat in pockets 28 in the ratchet wheel 15 and secure the sleeve thereto against both rotative and longitudinal movement. The sections also have 65 flanges 29 which form a flange adapted to lie just below the bearing 12, they also have other flanges 30 forming a flange at the lower end of the sleeve to support a hub 31 having a laterally extending lug 32, upon 70 which the forked arms 33 of the bent hand lever 16 are pivotally mounted by a pin 34.

In assembling the sleeve with the bearing, the ratchet wheel and the hand lever, the parts 23 are inserted and arranged with 75 their edges in contact as indicated in Fig. 3, then the segment 24 is inserted and its edge 35 laid against the edge 36 of one of the segments 23 after which the segment 24 is rotated about the contacting edges 35 80 and 36 to bring its opposite edge 37 into alignment with the adjacent edge 38 of the segment 23, on the opposite side of the shaft from the segment having the edge 36. The edge 37 of the segment 24 is cut away slightly to facilitate swinging this element into 85 position by the corner of the edge 38.

It is not necessary to fasten the segments of the sleeve together for they form a sort of loose locking engagement with each other, 90 which prevents collapsing of the sleeve and, therefore, prevents the assembly from becoming separated in handling or shipping. This unit may, therefore, be manufactured and supplied to car owners who may apply 95 it by merely inserting the conventional, or any suitable brake staff and bolting the bearing 12 to the car. This permits the assembling operations to be performed by especially skilled workmen in a shop equipped 100 with facilities for rapid and economical work, and permits the user to receive a unit which its workmen can mount with a minimum of time and labor.

It is preferable that ratchet wheels of 105 hand brake mechanisms have teeth on their lower sides so as to be protected from accumulation of ice, cinders and the like that would interfere with the operation. The locking pawl 17, or its equivalent, arranged 110

to engage another ratchet will have a tendency to force the shaft upwardly. With the present construction this upward thrust is resisted by the collar 29 coming in contact with the lower edge of the bearing 12. The sleeve 31 on which the hand lever is mounted is, therefore, left free from binding and can be swung back and forth with a minimum of effort. This feature of the present construction represents an improvement over that shown in my prior Patent No. 1,528,105 granted December 30, 1924, where an inaccurate mounting of the bracket 15 would permit the collar 29 to clamp the sleeve 28 against the bearing 13.

In this preferred embodiment the sleeve 22 has a cylindrical bore to receive the cylindrical portion of the brake shaft while the ratchet wheel is equipped with a hub 40 having a polygonal opening 41 to receive the polygonal portion 42 of the conventional brake shaft.

In some instances it will be found desirable to use a shaft that is polygonal for the greater part of its length and in that case the sections 23 and 24 will be formed with angular recesses which, together, make up a hole corresponding to the shape of the shaft, as indicated in Fig. 7, where 43 indicates the shaft and 44 and 45 indicates the sections of the sleeve.

I claim as my invention:

1. In a device of the class described, the combination of a rotatable shaft, a ratchet wheel fixed against rotation relative to the shaft, a bearing for the shaft, a sleeve swiveling the ratchet wheel to the bearing, a hand lever swiveled on the sleeve and a pawl carried by the lever and engaging the ratchet wheel.

2. In a device of the class described, the combination of a rotatable shaft, a ratchet wheel fixed to rotate with the shaft, a pawl for holding said shaft against unwinding, a hand lever rotatable about the shaft, a pawl carried by the hand lever and cooperating with the ratchet wheel to wind the shaft, a bearing for the shaft, and means for swiveling the ratchet wheel to the bearing above the hand lever.

3. In a brake mechanism a bearing adapted to be mounted upon a railway car, a ratchet wheel, a hand lever, and a sleeve engaged with the ratchet wheel and making a swivel connection between the ratchet wheel and the hand lever and the bearing.

4. In a brake mechanism a bearing adapted to be secured to a railway car, a ratchet wheel rotatable with respect to the bearing, a hand lever rotatable with respect to the bearing and the ratchet wheel, a sleeve including a plurality of longitudinal sections holding the ratchet wheel, the bearing and the hand lever in axial alignment, and flanges on the sleeve sections limiting move-

ment of said parts lengthwise to the sleeve.

5. In a brake mechanism a bearing adapted to be mounted upon a railway car, a ratchet wheel at one side of the bearing, a sleeve extending through the bearing and interlocked with the ratchet wheel to prevent their axial separation, and a flange on the sleeve engaging the bearing on the side opposite to the ratchet wheel.

6. In a brake mechanism a bearing adapted to be mounted upon a railway car, a ratchet wheel at one side of the bearing, a sleeve extending through the bearing and interlocked with the ratchet wheel to prevent their axial separation, a flange on the sleeve engaging the bearing on the side opposite to the ratchet wheel, a hand lever journaled on the sleeve adjacent to the flange, and means for holding the hand lever on the sleeve.

7. In a brake mechanism, a bearing adapted to be mounted upon a railway car, a ratchet wheel at one side of the bearing, a hand lever hub at the opposite side of the bearing and a sleeve extending through the hand lever hub and the bearing and into the ratchet wheel, said sleeve having external flanges limiting the movement of the ratchet wheel, the bearing and the hub with respect to the sleeve.

8. In a brake mechanism a bearing adapted to be mounted upon a railway car, a ratchet wheel and a lever arranged on opposite sides of the bearing and having bores aligned therewith, a sleeve in the aligned bores and comprising a plurality of longitudinal sections provided with external flanges limiting longitudinal movement of the parts with respect to the sleeve.

9. In a brake mechanism for railway cars, the combination of a bearing mounted on a car, a sleeve swiveled in the bearing, a brake staff received in the sleeve, a ratchet wheel above the bearing and connected with the sleeve and fixed against rotation relative to a brake staff, a holding pawl engaging the ratchet wheel with an upward thrust, a hand lever swiveled on the sleeve below the bearing, and a pawl for connecting the hand lever and the ratchet wheel.

10. In a brake mechanism for railway cars, the combination of a rotatable shaft, a bearing for the shaft, a ratchet wheel fixed against rotation relative to the shaft, a sleeve swiveled in the bearing and holding the ratchet wheel against movement away from the bearing, a holding pawl engaging the ratchet wheel and tending to move it away from the bearing, a hand lever rotatable about the shaft below the bearing, and a pawl connecting the lever and the ratchet wheel.

11. In a brake mechanism for railway cars, the combination of a rotatable shaft, a bearing for the shaft, a ratchet wheel hav-

ing teeth on its lower side mounted above the bearing and fixed against rotation with respect to the shaft, a holding pawl adapted to engage the teeth of the ratchet wheel with an upward thrust, a sleeve swiveled to the bearing and holding the ratchet wheel against movement away from the bearing, and a hand lever cooperating with the ratchet wheel to wind the shaft.

10 12. In a brake mechanism for railway cars, the combination of a rotatable shaft, a bearing for the shaft, a sleeve between the shaft and the bearing and having a flange below the latter, a ratchet wheel non-
15 rotatably mounted on the shaft above the bearing and made fast to the bearing by engagement with the sleeve, a holding pawl engaging the ratchet wheel and tending to move it upwardly away from the bearing
20 and the hand lever below the flange on the sleeve and cooperating with the ratchet wheel to wind the shaft.

13. In a brake mechanism for railway

cars, the combination of a bearing, a ratchet wheel rotatable with respect to the bearing, 25 a hand lever rotatable with respect to the bearing and the ratchet wheel, a sleeve including a plurality of longitudinal sections connecting the ratchet wheel, the bearing and the lever, and a rotatable shaft within 30 the sleeve and fixed to rotate with the ratchet wheel.

14. In a brake mechanism, a rotatable shaft, a bearing for the shaft, a ratchet wheel fixed against rotation with respect 35 to the shaft and at one side of the bearing, a holding pawl engaging the ratchet wheel and tending to move it away from the bearing, a hand lever rotatable about the shaft on the opposite side of the bearing from the ratchet wheel and means interposed between the hand lever and the bearing to prevent binding due to the thrust of the holding pawl.

In testimony whereof I affix my signature.
PERCY B. CAMP.
